DESIGN FOR A NAIL FILE

Willard L. Hults, Millburn, N. J.

Application October 4, 1934, Serial No. 53,484

Term of patent 3½ years

To all whom it may concern:

Be it known that I, Willard L. Hults, a citizen of the United States, residing at Millburn, in the county of Essex, State of New Jersey, have invented a new, original, and ornamental Design for a Nail File, of which the following is a specification, reference being had to the accompanying drawing, forming a part thereof.

The figure is a plan view of the nail file showing my improved design.

I claim:—

The ornamental design for a nail file, as shown.

WILLARD L. HULTS.
